UNITED STATES PATENT OFFICE

SIDNEY B. BLAISDELL, OF PHILADELPHIA, PENNSYLVANIA, ASSIGNOR TO FIDELITY MACHINE COMPANY, OF WILMINGTON, DELAWARE, A CORPORATION OF DELAWARE

BRAIDING MACHINE

Application filed February 1, 1929. Serial No. 336,730.

This invention relates to an apparatus for producing the improved type of braided packing, and the like, shown and described in my co-pending application for United States Letters Patent, filed October 25, 1928, Serial No. 314,980.

The invention described in the above mentioned co-pending application relates particularly to that kind of braided packing, which, prior to my invention, was produced by making the packing in a plurality of layers formed successively and disposed one around another, until a packing of the desired weight and cross-sectional dimensions was obtained.

The above process of manufacture was necessarily slow, for the reason that the formation of each superposed layer required the passing of the product through a separate braiding operation. The packing thus formed had certain inherent undesirable features as set forth in the said co-pending application.

The principal object of my present invention is to produce a machine by which a braided packing, of any desired weight, or cross-sectional dimensions may be manufactured in a single braiding operation, and which will form the completed packing in such a manner that all the threads of which the packing is composed will be interlocked with each other within the center of the packing, thus producing a superior article in considerably less time than has been possible heretofore, and obviating the objectionable features of the layer-built packing and the process by which such packing is manufactured.

In forming the improved interbraided packing described in the said co-pending application, I employ a plurality of series of threads, each series being composed of a plurality of individual threads. Each series of threads constitutes a segmental section of the complete packing, in the cross-section of the packing, throughout the length of the packing, and the threads of each series or segmental section are interbraided on the outer surface of the packing with the threads of the series or segmental section lying immediately adjacent thereto, thus the several segmental sections overlap the sections immediately ad-

jacent thereto, and all the threads are interbraided on the exterior of the packing and interlocked with each other within the center of the packing. Thus a compact braided packing of any desired weight is produced, the number of threads per series and their respective weights, and the number of series employed determining the ultimate weight and cross-sectional dimensions of the packing.

The weight, cross-sectional dimensions, and the cross-sectional configuration of the packing may be further modified to any desired extent by introducing at certain places within, and running longitudinally of, the packing any desired number of core threads around which the threads of the several series are braided. In this manner the packing may be caused to assume a round, square, rectangular, triangular or polygonal form in cross-section, depending upon the number, disposition and relative weights of the respective core threads.

The construction of the article, the method by which the article is manufactured, and the apparatus for producing the article, which forms the subject of my present invention will be fully disclosed in detail, reference being had to the accompanying drawings, of which:

Fig. 1 is an elevation, looking in the direction of arrow Z, Fig. 2, of a piece of packing made in accordance with the principles of my invention, with a portion cut away to show one thread of each of the series and the manner in which these threads of the several series are braided or interlaced with each other within the center of the packing;

Fig. 2 is a diagrammatic cross-sectional view taken on the line 2-2, Fig. 1, showing the packing in a somewhat expanded state, to illustrate clearly the manner in which the threads of each series or segmental section are braided together on the outside surface of the packing and how all the threads of all the series are interbraided within the center of the packing;

Fig. 3 is a diagrammatic view somewhat similar to Fig. 2, showing the method of braiding employed, and how the threads of

the several series are interbraided to form the complete packing;

5 Figs. 4 to 7 inclusive illustrate the paths traveled by the respective threads of the respective series during the braiding operation;

10 Fig. 8 is a cross sectional view of a piece of packing into which longitudinal core threads have been introduced to increase the weight and cross-sectional dimensions of the packing and to give the packing a substantially square cross-sectional form;

15 Fig. 9 is a diagrammatic perspective view illustrating the disposition of the various braiding thread carriers, the paths traveled thereby, and the positions of the core thread feeding tubes relative to the said paths of the braiding thread carriers;

20 Fig. 10 is a plan view of the bobbin carrier platform;

Fig. 11 is a sectional elevation taken on the line 11—11, Fig. 10, showing several of the bobbin carriers in place on the platform;

25 Fig. 12 is a sectional plan view taken on the line 12—12, Fig. 11;

Fig. 13 is a side view of one of the bobbin carriers, and

30 Fig. 14 is a rear view of the bobbin carrier shown in Fig. 13.

35 The packing illustrated in the drawings comprises four series of threads A, B, C and D, respectively.

Each series comprises nine individual threads illustrated at a^1 to a^9 inclusive, b^1 to b^9 inclusive, c^1 to c^9 inclusive, and d^1 to d^9 inclusive.

40 The threads are individually carried by individual bobbin carriers of conventional form, such as illustrated at 1 in Figs. 11, 13 and 14. These bobbin carriers 1 are adapted to be moved over a special form of bobbin carrier supporting platform 2, which is illustrated in Fig. 10. This platform is applied to a conventional form of braiding machine, 45 in the manner illustrated in Fig. 11. The bobbin carriers for the respective series of threads A, B, C and D are respectively adapted for movement along the paths and in the directions illustrated in Figs. 4, 5, 6 and 7 respectively, causing the threads of series A to be braided with the threads of the adjacent series B and adjacent series D on the outer surface of the packing; the threads of series B to be braided with the threads of adjacent series A and adjacent series C on the outer surface of the packing; the threads of series C to be braided with the threads of adjacent series B and adjacent series D on the outer surface of the packing; 55 and the threads of series D to be braided with the threads of adjacent series C and adjacent series A on the outer surface of the packing, as illustrated clearly in Figs. 2 and 3 of the drawings.

60 As shown clearly in Fig. 2, series A and

series B interlock on the outer face of the packing in the manner indicated at A—B; series B and C as illustrated at B—C; series C and D as illustrated at C—D; and series D and A as illustrated at D—A.

70 The path of travel of the threads of series A carries these threads into the interior of the packing and beyond and around the axial center X of the packing; series C which is located diametrically opposite to series A also travels into the interior of the packing and beyond and around the axial center X passing through and interlocking with series A about the center X as clearly shown in Figs. 1 and 2. Series B and series D, like 75 series A and C, are disposed diametrically opposite to each other at right angles to series A and C, passing through each other about the center X in the same manner as series A and C and also passing through 80 both of the said latter series A and C about the center X as illustrated. In this manner all the threads of all the series are interbraided with each other and intertwine with each other about the center X, forming a compact mass of intertwining threads within the 85 center of the packing, assuming in actual practice closely contracting positions such as shown by the broken out portion of Fig. 1 of the drawing.

90 As indicated in the several figures of the drawing, the paths traveled by alternate series during the braiding operation are in opposite directions, as shown by the arrows in Figs. 3 to 7 inclusive, thus the threads of series A and C follow what may be termed right hand irregular helical paths longitudinally of the packing, while the threads of series B and D follow left hand irregular helical paths longitudinally of the packing.

95 The number of threads per series and the number of series in the packing determine the pitch of the helical paths above noted and also determine the character of the braiding or weaving of the threads.

100 With nine threads per series and using four series as above noted, the appearance of the outer surface of the packing resembles that of a twill weave, in which each diagonally disposed thread passes over two threads 105 diagonally disposed in an opposite direction and under the next two threads disposed in said opposite direction, as clearly shown in Fig. 1. Obviously a change in the number of threads per series, or in the number of series employed, or both, will produce a different twill, such as over one and under one, or over one and under two, etc. Such changes, however, would be within the scope of the present invention.

110 The paths followed by the respective bobbin carriers 1, from which the threads of the several series are drawn, consist of a number of arc segments 3 connected end to end to form a continuous line of travel for the car- 115

riers belonging to each series, as clearly illustrated in Fig. 10. These are segments 3 are positioned around centers disposed in a predetermined relation to each other on the bobbin carrier supporting platform 2, the said centers bearing the relationship illustrated in Figs. 3 and 10, in which the said centers are respectively indicated at 10 to 25 inclusive, and intermediate the paths of the several series are formed spaces 26 to 30 inclusive.

Axially aligned with the centers 10 to 25 respectively and located in the spaces 26 to 30 respectively are core thread delivery tubes 15 10^a to 30^a respectively.

By running core threads through the core delivery tubes 10^a to 30^a, whereby the said core threads will extend longitudinally through the packing in positions corresponding to the centers 10 to 25 and the spaces 26 to 30 the weight and cross-sectional dimensions of the packing may be greatly increased and a substantially round packing produced.

By eliminating the core threads from certain of the centers and spaces the cross-sectional configuration of the packing may be changed to anything desired, such, for example, the square form illustrated in Fig. 8, in which a core thread E is inserted in the space 26, a core thread F at the center 10, a core thread G at the center 13, a core thread H at the center 16, and a core thread T at the center 19.

It will be noted that the core threads F and H are positioned diametrically opposite to each other and located on a line extending through the axial center X of the packing, which lies within the center space 26, and the threads G and T are also positioned diametrically opposite to each other on a line extending through the axis X, the line on which the core threads F and H are located being disposed at right angles to the line on which the core threads G and T are located, thus describing the outline of a square, and consequently producing a substantially square packing.

By placing core threads at those centers and in those spaces, which having connecting lines drawn through them would describe a triangle, such for instance as the centers 10 and 13 and the space 29, a triangular packing would be produced and so on through the various range of possible forms.

Regardless of the positioning of the core threads each core thread will be tightly bound in place by the braiding threads of the several series as they pass between and around the braiding threads of adjacent series and as they pass into the center of the packing and therein intertwine with the braiding threads of all the series about the axis of the packing.

As shown in Fig. 11, the bobbin carrier supporting platform 2 is supported above and in spaced relation with respect to a plate 50,

which constitutes the main bed plate of a conventional form of braiding machine.

In the cutting of the arcs 3, 3 to form the undulated and intertwining paths A¹, B¹, C¹ and D¹, in which the groups of bobbin carriers 1 which carry the threads a¹ to a⁹, b¹ to b⁹, c¹ to c⁹ and d¹ to d⁹ of the series A, B, C and D respectively are adapted to move, the portions 10^b to 30^b of the plate 2 are completely disconnected from each other and from the rim portion 2^a of the plate 2. These disconnected portions 10^b to 30^b are respectively supported and maintained in the correct relative position one to the other by the core tubes 10^a to 30^a in the manner illustrated in Fig. 11.

As shown in Fig. 11, each of the core tubes 10^a to 30^a comprises a body portion 55, which is reduced in diameter at its opposite ends as indicated at 56 and 57 respectively, thereby forming shoulders 58 and 59 on the respective ends of each of the said core tubes. The reduced portions 56 and 57 respectively extend through openings 60 and 61 formed in the base plate 50 and in the bobbin carrier supporting plate 2 respectively.

The reduced portions 56 and 57 are further reduced as indicated at 62 and 63 respectively, the latter reductions being externally threaded for the reception of securing nuts 64 and 65, which respectively bear against the lower face of the plate 50 and the upper face of the supported portion of the plate 2, thereby seating and rigidly maintaining the said plates against the shoulders 59 and 60 of the core tubes.

As clearly shown in Fig. 11, each core tube is provided with an axially aligned passage or bore 66 through which a core thread is adapted to pass from a bobbin located under the bed plate 50 to the braiding point of the machine which is located some distance above the bobbin carrier supporting plate 2, as shown in Fig. 9.

The rim portion 2^a of the plate 2 is secured to and spaced apart from the bed plate 50 by means of bolts 67, as illustrated in Fig. 10. The bolts 67 may be shouldered in the manner above noted, or a spacing sleeve may be placed around the bolt between the plates 2 and 50 to maintain the said plates in spaced relation one to the other.

As indicated in Figs. 10 and 11, certain of the core tubes may be provided with tubular extensions 68 in order to deliver the core thread passing therethrough in the plane above the tops of the bobbin carriers 1, to prevent the said core threads from becoming entangled with the said bobbin carriers.

Rotatably mounted on the body portion 55 of each of the core tubes 10 to 25 inclusive is a gear wheel 10^c to 25^c inclusive. As shown in Fig. 10, the gears 10^c, 13^c, 16^c, 19^c, 22^c, 23^c, 24^c and 25^c are of a greater diameter than the gears 11^c, 12^c, 14^c, 15^c, 17^c, 18^c, 20^c and 21^c.

The gears having the larger diameter are each provided with a series of five equiangularly spaced and radially extending pairs of projections or horns 68, 68, and each of the 5 gears having the smaller diameter are provided with a series of four pairs of projections or horns 69, 69, as clearly illustrated in Fig. 12. These horns are adapted to engage lugs 70, 70 formed integral with and depending from the bases 71, 71 of the bobbin carriers 1.

The base 71 of each bobbin carrier 1 comprises a pair of spaced plates 72 and 73 which are integrally connected by an elongated fin 15 74. The fins 74 extend through and ride in the slots formed in the plate 2 which constitute the paths A¹, B¹, C¹ and D¹ in which the bobbin carriers of the respective series A to D are adapted to travel during the braiding 20 operation.

Each bobbin carrier 1 also is provided with a spindle 75 which supports a thread bobbin 76. Each bobbin carrier 1 also is provided with a thread guiding post 77. On the thread 25 guiding post 77 is slidably mounted a tension weight 78. The thread from the bobbin 76 is led from the bobbin through an eye 79 formed in the post 77, under the lower edge of the tension weight 78, and then up through an eye 30 80 formed in the upper end of the post 77, from which the thread passes to the braiding point of the machine which is located some distance above the plate 2, as shown in Fig. 9.

The braiding operation is carried on in the 35 same general manner as the ordinary braiding operation with the exception that in place of each bobbin traveling completely around the bed plate of the machine its movement is confined to the segmental path allotted to 40 the particular series to which the particular bobbin carrier belongs, these paths being clearly indicated in Figs. 4, 5, 6, 7 and 10. The bobbin carriers are engaged by the projections or horns on the gears rotating about 45 the centers 10 to 25 inclusive, and as the fin 74 of each bobbin carrier passes along the path allotted to that particular series the horn of one gear moves the depending projection 70 of the bobbin carrier 1 into the proper position to be engaged by a horn of the gear meshing therewith, the transfer from one gear to the other taking place at the point along the path where a change of direction in the said 50 path occurs.

55 As shown in Fig. 9, the braiding point Y of the machine is in substantially vertical alignment with the central core tube 26; and as shown in Fig. 10 this core tube 26 is located at a point P lying within each of the individual paths A¹, B¹, C¹ and D¹ and is, therefore, common to all of said paths.

As shown in Fig. 10, the outer portions of 60 above mentioned individual paths intersect at points I, and these intersecting points are 65 remotely situated with respect to the said com-

mon point P; the inner portions of the said individual paths again intersect at points I¹ and also at points I², the points I¹ and I² being located intermediate the remotely situated intersecting points I and the common point P, and the intersecting points I² being located rather close to or adjacent the said common point P.

Also as shown in Fig. 10, the innermost 70 portions of the respective individual paths pass around the common point P to the side thereof opposite to that occupied by the said outer portions of the respective paths.

I claim:

1. In a braiding machine employing a plurality of thread carriers, a guide for said carriers describing a plurality of individual paths to be respectively traveled by different carriers, said paths intersecting at points 80 remotely situated with respect to a common point on said guide and intersecting again adjacent said common point, said common point being disposed within each and all of said intersecting paths.

2. In a braiding machine employing a plurality of thread carriers, a guide for said carriers describing a plurality of individual paths to be respectively traveled by different carriers, said paths intersecting at points 90 remotely situated with respect to a common point on said guide, passing around said common point, and intersecting again adjacent 95 said common point.

3. In a braiding machine employing a plurality of thread carriers, a guide for said carriers describing a plurality of individual paths to be respectively traveled by different carriers, said paths intersecting at points 100 remotely situated with respect to a common point on said guide and intersecting again at 105 points intermediate said common point and the said remotely situated intersecting points, said common point being disposed within each and all of said intersecting paths.

4. In a braiding machine employing a plurality of thread carriers, a guide for said carriers describing a plurality of individual paths to be respectively traveled by different carriers, said paths intersecting at points 110 remotely situated with respect to a common point on said guide, passing around said common point, and intersecting again at points 115 intermediate said common point and the said remotely situated intersecting points.

5. In a braiding machine employing a plurality of thread carriers, a guide for said carriers describing a plurality of individual paths to be respectively traveled by different carriers, said paths intersecting at points 120 remotely situated with respect to a common point on said guide and intersecting again at points intermediate said common point and the said 125 remotely situated intersecting points, and again intersecting at points adjacent said common point, said common point being dis- 130

posed within each and all of said intersecting paths.

6. In a braiding machine employing a plurality of thread carriers, a guide for said carriers describing a plurality of individual paths to be respectively traveled by different carriers, said paths intersecting at points remotely situated with respect to a common point on said guide and intersecting again at points intermediate said common point and the said remotely situated intersecting points, passing around said common point, and again intersecting at points adjacent said common point.

15 7. In a braiding machine employing a plurality of thread carriers, a guide for said carriers describing a plurality of individual paths to be respectively traveled by different carriers, said paths intersecting at points located around, and remotely situated with respect to a common point on said guide and intersecting again adjacent said common point, said common point being disposed within each and all of said intersecting paths.

25 8. In a braiding machine employing a plurality of thread carriers, a guide for said carriers describing a plurality of individual paths to be respectively traveled by different carriers, said paths intersecting at points located around, and substantially equidistantly from, and remotely situated with respect to a common point on said guide and intersecting again adjacent said common point, said common point being disposed within each and all of said intersecting paths.

9. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, said common point being disposed within each and all of said intersecting paths.

55 10. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, and a core thread delivery tube located at said common point,

said common point being disposed within each and all of said intersecting paths.

11. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, and a core thread delivery tube located at predetermined ones of said centers, said common point being disposed within each and all of said intersecting paths.

15 12. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, and a core thread delivery tube located at each of said centers, said common point being disposed within each and all of said intersecting paths.

25 13. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, and a core thread delivery tube located at predetermined points within the said paths, said common point being disposed within each and all of said intersecting paths.

35 14. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations,

- said paths intersecting at points remotely situated with respect to a common point on said guide, and intersecting again adjacent said common point, a core thread delivery tube located at said common point, and a core thread delivery tube located at each of a predetermined number of said centers said common point being disposed within each and all of said intersecting paths.
15. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, a core thread delivery tube located at said common point, a core thread delivery tube located at each of a predetermined number of said centers, and a core thread delivery tube located at each of a predetermined number of points located within the said paths and removed from said common point and said centers, said common point being disposed within each and all of said intersecting paths.
16. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, and means rotatably mounted for movement about each of said centers and adapted to engage the respective carriers and thereby advance the said carriers along said paths, said common point being disposed within each and all of said intersecting paths.
17. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, a core thread delivery tube located at each of said centers, gear wheels rotatably mounted on said core tubes respectively, and projections on said gear wheels adapted to engage said carriers and advance them along said paths, said common point being disposed within each and all of said intersecting paths.
18. In a braiding machine employing a plurality of thread carriers, a guide for said carriers describing a plurality of individual paths to be respectively traveled by different carriers, each path comprising a plurality of undulations, the undulations of each path being respectively located opposite to the respective undulations of another of said paths about centers located respectively within opposed pairs of said undulations, said paths intersecting at points remotely situated with respect to a common point on said guide, and intersecting again adjacent said common point, and means rotatably mounted for movement about each of said centers and adapted to engage the respective carriers and thereby advance the said carriers along said paths, the carriers traveling in each respective path moving in a direction opposite to the direction of movement of the carriers of the next adjacent path, said common point being disposed within each and all of said intersecting paths.
19. In a braiding machine employing a plurality of thread carriers, a guide for said carriers describing a plurality of individual paths to be respectively traveled by different carriers, said paths intersecting at points remotely situated with respect to a common point on said guide and intersecting again adjacent said common point, said remotely situated points of intersection being located substantially on a circle swung from said common point on said guide, said common point being disposed within each and all of said intersecting paths.
- SIDNEY B. BLAISDELL.
